UNITED STATES PATENT OFFICE.

FRANK WETTERAUER, OF ERIE, PENNSYLVANIA, AND GUSTAVE A. WEGNER, OF ROCHESTER, NEW YORK.

APPARATUS FOR DESICCATING HUMAN CORPSES.

1,127,140.

Specification of Letters Patent.

Patented Feb. 2, 1915.

Application filed April 27, 1914. Serial No. 834,616.

To all whom it may concern:

Be it known that we, FRANK WETTERAUER and GUSTAVE A. WEGNER, citizens of the United States, residing at, respectively, 5 Erie, in the county of Erie and State of Pennsylvania, and Rochester, in the county of Monroe and State of New York, have invented a new and Improved Apparatus for Desiccating Human Corpses, of which 10 the following is a specification.

This invention relates to means for the preservation of human corpses, the employment of which is made use of when, as is often desirable, bodies are to be preserved 15 for some length of time, better than can be accomplished by the usual method of embalming, as for instance, for transportation or for burial in a family vault or chapel which now and then must be opened again. 20 It is well known that human bodies, after death, will be preserved wherever, by either climatic conditions or on account of altitude, a very dry atmosphere prevails which facilitates a rapid evaporation of the water 25 which forms such an integral part in the physical structure and chemical composition of the human body.

To bring about such conditions by artificial means in a convenient and perfectly 30 sanitary manner is the object of our invention, and we accomplish this in the following manner: The body is placed in an air-tight vault in a casket which is provided with a plurality of comparatively small 35 openings which may be so arranged that they can be conveniently closed later. The opening to the vault is then closed, air-tight, either by means of a door and bolts or by the insertion of a stone or marble slab. 40 There are, preferably, a number of these vaults arranged in tiers in a mausoleum or chapel, and they are connected by suitable pipes to either a vacuum pump or an exhaust fan of high efficiency to bring about 45 substantially a vacuum in the vault or vaults, and as by this procedure any moisture which is given out by evaporation is as rapidly removed as it is generated the body becomes quickly desiccated. To accelerate 50 the process the vaults may be heated and we intend to use for this purpose the exhaust steam from the motor driving the aforesaid vacuum pump or exhaust fan by circulating such steam through heating coils placed into 55 chambers provided therefor in the walls

forming the partitions between the several vaults. In order to dispose of the air, gases or vapors extracted from one or more of the vaults by the vacuum pump or exhaust fan, the same are conducted through the 60 above mentioned pipes to said pump or exhaust fan, and from the latter by means of a suitable connection to the furnace of a boiler used for the generation of steam to supply a steam engine driving said vacuum 65 pump or exhaust fan. In places where electricity may be cheaply had for motive power, it will, nevertheless, be necessary to have a furnace into which the gases taken from the vault or vaults may be discharged, 70 in order to change their chemical composition by exposing them to a high degree of heat, before being discharged through a chimney or stack into the open air. The furnace, in this case, may be utilized to 75 heat a low pressure steam boiler or hot water heater, and either the steam or hot water thus produced used for circulation through the heating coils as and for the purpose above described. 80

The accompanying drawings illustrating, diagrammatically, a mausoleum or chapel in part and an apparatus installed therein constructed in accordance with our invention are as follows. 85

Figure 1 is a vertical sectional view of the mausoleum or chapel section with the apparatus shown in side elevation; Fig. 2, a horizontal sectional view thereof with the apparatus shown in plan view; and Fig. 3, a 90 sectional detail of the side wall of a casket showing one of the openings therein the purpose of which will be explained.

Similar reference characters refer to similar parts throughout the several views. 95

The numeral 1 designates a mausoleum or chapel, in part, in which there may be located one or a plurality of air-tight chambers or mortuary vaults 2 arranged in tiers, as shown. These vaults may be built of 100 concrete, tile or similar material and lined with enameled metal or marble, or a metal sheet may be built right in with each concrete or tile wall to insure the vaults, when closed, against any access of air. The opening to each of the vaults 2, in Figs. 1 and 2 herein shown, is closed by a metal door 3 swinging in a cast frame 4 built into the vault opening, and by means of suitable packing and bolts these doors can be made 110

air-tight. One or more locks may also be attached to each of the doors, the keys of which, if several locks are used, may be held by different persons to insure against wanton 5 ton opening of any of the vaults; or the vaults may each be closed by a stone or marble slab securely cemented and sealed, such closures not being shown but which it is believed will readily be understood. 10 From an opening in the rear wall and near the bottom of each of the vaults 2, a short laterally extending pipe 5 leads to and is connected with one or a series of vertically extending pipes 6 connected with a larger 15 and main exhaust pipe 7 which, in turn, is connected to a vacuum pump 8, and from such pump a pipe 9 leads to the furnace 10 of the boiler 11 where the gases drawn from one or more of the vaults 2 by means of the 20 vacuum pump and through the connecting pipes, above mentioned, are robbed of their combustible constituents and made harmless. Each of the pipes 6 is provided with a suitable valve 12 whereby the action of 25 the pump 8 will effect only predetermined ones of the vaults 2.

In the drawings, further, 13 represents a steam engine for driving the pump 8, and 30 14 the fly-wheel thereof mounted on a shaft 15 journaled in suitable bearings and having on its opposite ends the cranks 16 and 17 of the engine 13 and pump 8, respectively, the piston and connecting rods of the engine and pump not being shown. Steam is 35 supplied to the engine 13 from the boiler 11 through the pipe 18, while the exhaust steam from the engine is conducted through the main exhaust pipe 19 and branches 20 leading therefrom and caused to circulate 40 through the coils 21 located in chambers therefor in the walls forming the partitions between the several vaults 2 for the purpose of heating said partition walls and thereby the air within said vaults. Each 45 branch pipe 20 has a valve 22 located therein in order that the steam may be turned off from any of the coils 21 when it is not required to heat certain ones of the vaults 2.

All of the above mentioned apparatus is 50 located, preferably, as shown, in the basement beneath the floor 23 of the mausoleum.

In Fig. 3 there is shown a portion of the side wall of a casket 26 in which there is a comparatively small opening fitted with an 55 internally threaded sleeve 24. This sleeve is securely held in place by means of suitable screws, not seen, engaging through an outwardly extending flange thereon and receives the threaded extension of the cap member 25, such cap member being adapted to close the opening in the casket and secured to place from the outside of the casket. There may be any desired number of these openings in a casket although we have 60 65 found that two, one at each end of the cas-

ket, are sufficient. The cap members 25 are of course removed when the casket is placed within a vault for the purpose of bringing about the desiccation of the body therein.

It will readily be understood that, without departing from the spirit of our invention, an exhaust fan may be substituted for the vacuum pump 8, such fan being driven from any suitable source of power, and that the steam from the boiler 11 may be conducted directly therefrom to the heating coils 21.

From the foregoing description of the desiccating apparatus it is believed that the construction thereof and method of using the same are sufficiently clear to call for no further explanation herein.

What we claim is:

1. In a mausoleum, the combination of a vault the surrounding walls of which are made air-tight, an opening to said vault, an air-tight closure for said opening, a suction device operating to create a vacuum in said vault, means for operating the same, and pipe connections between said suction device and said vault substantially as and for the purpose described.

2. In a mausoleum, the combination of a vault the surrounding walls of which are made air-tight, an opening to said vault, a casket provided with a plurality of openings and removably contained within said vault, an air-tight closure for said opening, a suction device operating to create a vacuum in said vault, means for operating the same, and pipe connections between said suction device and said vault substantially as and for the purpose described.

3. In a mausoleum, the combination of a vault the surrounding walls of which are made air-tight, an opening to said vault, an air-tight closure for said opening, a suction device operating to create a vacuum in said vault, means for operating the same, pipe connections between said suction device and said vault, a furnace, and a discharge pipe leading from said suction device to said furnace for delivering thereto the air and gases from said vault.

4. In a mausoleum, the combination of a vault the surrounding walls of which are made air-tight, an opening to said vault, an air-tight closure for said opening, a suction device operating to create a vacuum in said vault, means for operating the same, pipe connections between said suction device and said vault, a boiler and a furnace for heating the same, a discharge pipe leading from said suction device to said furnace for delivering thereto the air and gases from said vault, heating coils located in chambers therefor in the side walls of said vault, and pipe connections between said coils and said boiler.

5. In a mausoleum, the combination of a

- plurality of vaults arranged in tiers, the surrounding walls of said vaults being made air-tight, an opening to each of said vaults, air-tight closures for said openings, chambers formed in the side walls of said vaults and heating coils located therein, a suction device operating to create a vacuum in predetermined ones or all of said vaults and means for operating the same, pipe connections between said suction device and said vaults, such connections having valves located therein, a boiler and a furnace for heating the same, a discharge pipe leading from said suction device to said furnace for delivering thereto the air and gases from said vaults, pipe connections between said boiler and said heating coils, and valves located in said pipe connections as and for the purpose described.
6. In a mausoleum, the combination of a plurality of vaults arranged in tiers, the surrounding walls of said vaults being made air-tight, an opening to each of said vaults, air-tight closures for said openings, chambers formed in the side walls of said vaults and heating coils located therein, a pump operating to create a vacuum in predetermined ones or all of said vaults, an engine for operating said pump, pipe connections between said pump and said vaults, such connections having valves located therein, a boiler and a furnace for heating the same, a discharge pipe leading from said pump to said furnace for delivering thereto the air and gases from said vaults, a supply pipe from said boiler to said engine, pipe connections for conducting the exhaust steam from said engine to said heating coils, and valves located in said last named connections, all substantially as described.
